DESIGN FOR A COMBINED DRESSER CABINET AND BUREAU OR THE LIKE

Irving H. Stern, Boston, Mass.

Application February 21, 1935, Serial No. 55,546

Term of patent 7 years

To all whom it may concern:

Be it known that I, Irving H. Stern, a citizen of the United States, residing at Boston, in the county of Suffolk and State of Massachusetts, have invented a new, original, and ornamental Design for a Combined Dresser Cabinet and Bureau or the like, of which the following is a specification, reference being had to the accompanying drawing, forming a part thereof.

In the drawing,—

Fig. 1 is a perspective view of a combined

dresser cabinet and bureau illustrating my design, and showing the hinged mirror in closed position;

Fig. 2 is a perspective view of the dresser cabinet showing the hinged mirror in open position.

The dominant features of the design are shown by full lines.

I claim:

The ornamental design for a combined dresser cabinet and bureau or the like as shown and described.

IRVING H. STERN.
